UNITED STATES PATENT OFFICE.

DANIEL W. ADAMS, OF GLENDALE SPRINGS, NORTH CAROLINA.

PARACHUTE-LAUNCHING DEVICE.

1,069,682.

Specification of Letters Patent. Patented Aug. 12, 1913.

Application filed October 6, 1911. Serial No. 653,144.

To all whom it may concern:

Be it known that I, DANIEL W. ADAMS, a citizen of the United States, residing at Glendale Springs, in the county of Ashe and State of North Carolina, have invented new and useful Improvements in Parachute-Launching Devices, of which the following is a specification.

This invention relates to apparatus for projecting or launching a parachute together with an aviator from an aeroplane while in flight at any moment when it is deemed advisable due to an accident or for other reason.

The majority of fatal accidents to aeronauts have resulted from their inability to extricate themselves from the disabled or unmanageable machine. Even when the aeronaut has been provided with a parachute, it is almost impossible for him to launch it, and if the aeroplane is careening or darting downward with great speed the difficulty is greatly enhanced.

The object of my invention is to provide an apparatus which will automatically lift the aviator and the parachute and forcibly project them from the aeroplane as soon as the releasing device is operated.

It is my purpose to arrange the apparatus in such a manner that the aviator will be at all times supported upon the standard of the parachute, and to place the releasing device within easy access of his hand so that he may at any moment be carried up out of the aeroplane and be safely supported and sustained while gradually brought to earth, without being endangered by the wrecked or uncontrolled machine.

I further provide for the gradual initial movement of the parachute and for an accelerated velocity as it is projected from the aeroplane.

My invention will be comprehended from the following description in connection with the accompanying drawings illustrating one embodiment thereof, in which—

Figure 1 is a side elevation of my launching apparatus, partly in section; Fig. 2 is a sectional elevation of the same taken at right angles to Fig. 1; Fig. 3 is a top and sectional view on the line III—III of Fig. 2; and Fig. 4 is an enlarged detail view of the compressed air tank and the valve operating connections.

The parachute and launching mechanism are located in the forward part of the aeroplane in the position usually occupied by the aeronaut. The canopy 1, of the parachute is normally folded and is carried by a hollow stem or tube 3, which telescopes over an inner tube 4, extending below the platform of the lower plane and securely fastened by brace rods 6 and angle pieces 7. The inner tube thus constitutes a rigid standard for the parachute, the inner and outer tubes being preferably accurately fitted with a ground joint and having a film of oil therebetween. The saddle or seat 9 may be fastened to rings or sleeves 10 surrounding the tube 3 and supported upon lugs 12. The seat may be swung either in front, in the rear, or at one side of the tube, and locked in position by means of thumb-screws 14, so that the aviator may adjust his position with relation to the steering levers to suit his convenience. Foot-rests or stirrups 16, may be secured to either side of the rod, which will assist the aviator in supporting himself firmly when the parachute is in flight.

For the purpose of propelling the parachute upward and forcibly ejecting it from the aeroplane, I utilize the outer and inner tubes as motor barrel or cylinder and piston respectively. The outer tube or barrel 3 is provided with a diaphragm 18; and the upper end of the inner tube 4 is closed except for a port 20, the telescoping walls of the tubes being preferably ground to a close fit and made air-tight by means of a thin film of oil. The lower portion of the inner tube is closed by a diaphragm 22, and provided with a port which is connected by a small tube 24 with a compressed air tank 25 supported in hangers 26 and constructed to withstand a pressure of over 250 lbs. per square inch. The delivery 27 from the tank is controlled by a reducing valve of any suitable type, having an operating shaft 28 mounted in bearings and carrying the pinion 29 and a graduated dial 30 to indicate the position of the valve.

In order that the valve governing the tank outlet connected with the tube 24 may be readily controlled by the aviator, I provide an actuating rod 31 having at its lower end a rack 32 engaging the pinion, and at its upper end a handle 33. The rod may pass

through a housing or channel 35 upon one side of the tube 3, the travel or movement thereof being limited by the length of the slot 36. A latch 34 may be provided to prevent accidental movement of the handle.

10 The main portion of the outer tube terminates above the platform of the lower plane and is provided upon one side with an extension or depending portion carrying at its lower end a rack 38 in alinement with the rack 32, these racks being spaced apart a considerable amount, say 18 inches or more, for a purpose to be hereinafter described.

15 The operation of the launching mechanism will be understood from the foregoing description.

If the aviator discovers that his machine is no longer under control, or if an accident 20 happens to the machine which threatens to endanger his life, he may instantly start the launching mechanism into operation by lifting the handle 33, thereby sliding the rack 32 upward and rotating the pinion 29 to 25 open the reducing valve slightly and permit a certain pressure of compressed air to pass from the tank into the inner tube 4. The air under pressure passes from the inner tube through the port 22, which acts as a 30 regulator, and into the small chamber 3^a between the top of the inner tube and the diaphragm 18 of the outer tube. The pressure against the diaphragm immediately starts the outer tube upwardly, carrying the 35 parachute, and the aviator, who is securely mounted, being seated upon the saddle with his feet resting upon the stirrups 16 and one hand gripped upon the handle 33, his other hand or arm being placed around the tube.

40 The movable structure will start smoothly, and will accelerate in speed, this effect being increased, if desired, by extending the length of the rack 32. After the parts have been lifted between one and two feet, the lower 45 rack 38 engages the pinion 29 to open the tank valve to its full extent, throwing the full pressure into the tubes and projecting the parachute from the machine with sufficient velocity to carry the aviator to a distance 50 above the machine, thus not only setting him entirely free, but in case he is near the ground, lifting him to a height sufficient to clear obstructions and enable the parachute to sustain his weight.

55 In order that the aviator may be easily projected through the upper plane 40, in case the seat is located under the forward portion thereof, the fabric of the plane may be provided with a thinner or easily tearable 60 section, as indicated at 40^a.

Owing to the fact that the aviator is seated near the lower end of the projected apparatus, his weight will cause the center of gravity of the parachute to be low, and it is 65 evident that it will right itself very quickly,

even though it is projected from the aeroplane at an instant when it is careening at an angle or even pitching toward the earth.

The canopy of an ordinary parachute will spread as soon as it assumes a substantially 70 vertical descent, and if desired a parachute of the self-opening type may be employed, in which the opening is under control of the aviator.

If it is desired to test the operation of the 75 parts before starting, the relief cock 42 may be opened and the valve may then be opened to indicate whether it is in working order and whether the tank is under proper pressure.

I have described in detail the apparatus illustrated in the accompanying drawings for the purpose of disclosing one embodiment 85 of my invention, but I am aware that many changes may be made in the structure and arrangement of parts without departing from the spirit of my invention.

I claim:

1. A parachute launching-apparatus comprising a parachute having a tubular stem 90 constituting an outer shell and adapted to serve as a motor cylinder, a source of motive-power, means for connecting said source with the interior of said tubular stem, and means for controlling the release of said motive-power.

2. A parachute launching-apparatus comprising a parachute having a hollow standard or stem constituting an outer shell and adapted to serve as a motor cylinder, a 100 source of fluid-pressure, connecting means between said source and said hollow standard, and valve-mechanism for controlling the delivery of said fluid-pressure into said standard.

3. A parachute launching-apparatus comprising a parachute having a standard or stem, a source of motive-power, means connecting said source with said standard, manually controlled means for causing an initial 110 operation of said motive-power, and auxiliary means for causing a further operation thereof.

4. A parachute launching-apparatus comprising a parachute having a standard or stem, a source of motive-power, means connecting said source with said standard, manually controlled means for causing an initial 115 operation of said motive-power, and automatic means for causing an increased operation thereof.

5. Apparatus for launching a parachute from an aeroplane, comprising a parachute having a hollow stem adapted to serve as a motor cylinder, means for supporting said stem, a source of motive-power, means for connecting said source of power with said stem, and controlled means for successively releasing said source of power at different 125 pressures.

6. Apparatus for launching a parachute from an aerocraft, comprising a parachute having a hollow stem, an operator's support carried thereby, means for supporting said 5 stem, a source of motive-power, means for connecting said source of power with said stem, and means for successively releasing said source of power in increasing amounts.

7. Apparatus for launching a parachute 10 from an aerocraft, comprising a parachute having a hollow stem, a hollow support adapted to telescope within said stem, a reservoir for compressed motive-fluid connected with said hollow support, and manually controlled means for governing the flow of motive-fluid from said reservoir.

8. Apparatus for launching a parachute from an aerocraft, comprising a parachute having a hollow stem, a reservoir for compressed motive-fluid connected with said hol- 15

20 low support, a valve for controlling the flow of motive-fluid from said reservoir, manually operated means for opening said valve a predetermined amount, and auxiliary means for increasing the valve opening.

25

9. An aerial navigating device comprising an aerocraft, a parachute having a standard or stem, a support on said stem for holding an operator, a support for said standard carried by said aerocraft, means for projecting said parachute from said aerocraft, and means adjacent said support for controlling the operation of said projecting means.

30

In testimony whereof I have hereunto set my hand in presence of two subscribing witnesses.
